UNITED STATES PATENT OFFICE.

CLARENCE D. PLATT, OF BRIDGEPORT, CONNECTICUT.

ELECTRIC SWITCH.

1,309,153.

Specification of Letters Patent.

Patented July 8, 1919.

Application filed May 18, 1918. Serial No. 235,241.

To all whom it may concern:

Be it known that I, CLARENCE D. PLATT, a citizen of the United States of America, residing at Bridgeport, Conn., have invented 5 a new and useful Electric Switch, of which the following is a specification.

My present invention relates to switches 10 of the quick-acting or snap variety, for instance, those of the push button type. The contacts employed in these switches, to be of the necessary resiliency and durability are made of a high grade of spring material such as phosphor-bronze. Objection has been found however, in the use of these 15 switches because of the fact that the spring contacts have a certain musical quality which causes the switch to emit a distinct musical sound or "twang" when the switch is operated, this sound of course being intensified when the switch is mounted in place in a wall or other support which would act as a sound-board.

In my present invention I have endeavored to overcome the objection noted and 25 have, in fact, succeeded in silencing the spring contacts without impairing the action of the switch in any way.

Briefly my invention resides in the provision of means for checking the sound-producing vibrations of the spring switch contacts, such means consisting in the embodiment herein disclosed, of stop shoulders disposed for engagement by the spring contacts when said contacts are released from the 30 conducting element which engages therewith.

Other features of the invention and the details of construction will appear as the specification proceeds.

The accompanying drawing illustrates 40 the invention embodied in two different forms but it will be understood that the invention is susceptible of further modification without departure from the true spirit and scope thereof.

In this drawing:-

Figure 1, is a fragmentary sectional view 45 of an improved form of push button switch having the invention incorporated therein, said view being taken substantially on the plane of the line 1—1 of Fig. 2.

Fig. 2, is a top plan view of the switch, omitting such parts as have no bearing on the present invention.

Fig. 3, is a sectional view taken substantially on the plane of the line 3—3 of Fig. 2,

the spring contacts in all views thus far being free and disengaged from the co-operating contact element.

Fig. 4, is a view similar to Fig. 3, illustrating the spreading action of the spring contacts by the bridging member which engages therewith.

Figs. 5 and 6 are perspective and sectional views respectively, of a slightly modified 65 form of the invention.

7 designates the hollow insulating base of a push button switch of approved construction and provided with a swinging contact element 8 for engagement with the spring 79 contacts.

The spring contacts are designated 9 and 10 and are shown secured upon the supporting shoulders 11 by screws 12 passed through the back of the base into engagement with 75 the terminals 13 overlying the base portions of the spring contacts.

These spring contacts, as clearly shown in Figs. 2 and 3, stand out from their supports so as to be freely yieldable under the impact 80 of the relatively movable contact 8 which bridges or connects them after the manner indicated in Fig. 4.

In the first construction illustrated, the sound producing vibrations of the spring 85 contacts are checked by means of an abutment 14 disposed between the two spring contacts and providing the stop shoulders 15 for engagement by said contacts when the same are free of the movable bridging 90 contact (Figs. 2 and 3). These stop shoulders 15 are spaced apart a distance less than the length of the bridging contact 8 so that said movable contact will have the effect of spreading the spring contacts and thus placing them under such tension as to insure perfect electrical conductivity. The forwardly projecting end portions of the spring contacts may be flared somewhat as indicated at 16 to provide inclined surfaces for 100 wedging engagement by the movable contact member.

From this it will be seen that the movable contact member depresses the outstanding spring contacts toward their respective supports and that when freed from pressure of said movable contact, said spring contacts will immediately spring out into engagement with the stop shoulders provided therefor and thus be prevented from vibrating or 105 checked to such an extent as to prevent the giving off of audible sound. The stop

shoulders furthermore serve to accurately position the spring contacts without interfering with their yielding properly under impact of the movable contact element.

- 5 Another method of checking the undesirable vibrations of the spring contacts is illustrated in Figs. 5 and 6 consisting in providing the contacts, here designated '9, with an integral dependent tongue 17 which
- 10 stands normally in engagement with the stop shoulder 15' as indicated in Fig. 6. In this construction the contacting wing portion 16' is free to yield under pressure of the movable contact and is prevented from
- 15 objectionably vibrating when disengaged from the movable contact by reason of the engagement of the vibration checking tongue 17 with the stop shoulder 15'.

It will be apparent from the foregoing that my invention provides a practical and at the same time very simple construction for checking and preventing the objectionable, noisy vibrations heretofore present in switches of the character referred to.

25 I claim:—

1. In a snap switch, a stationary support, a movable contact member and a yielding contact member, said yielding contact member having a stationary end, a movable contact end adapted to be engaged by the movable contact member and a portion intermediate said ends tensioned against the support when the switch is in the open circuit position sufficiently to prevent audible vibrations.

30 2. In a snap switch, a pair of opposed spring contacts, a movable switch member engageable therewith, means for snapping said movable switch member into and out of engagement with said spring contacts, sta-

tionary shoulders interposed between the spring contacts, said spring contacts having vibration checking portions tensioned against the shoulders when said spring contacts are released from engagement with the 45 movable switch member.

3. In a snap switch, a supporting base, a contact having a base portion secured rigidly to said support and a yielding spring portion projecting out of engagement with 50 the support so as to yield free of said support, a movable contact member arranged to depress the freely yielding portion of the first contact toward the support and a stationary stop shoulder positioned in the path 55 of rebound of the yielding portion of the spring contact and adapted thereto to be engaged by and to immediately check vibrations of said free spring portion of the contact when said contact is released from 60 engagement with the movable contact member.

4. In a snap switch, a supporting base, a spring contact having a foot portion secured to the base and an angularly extending 65 spring contact portion free to vibrate independently of the supporting base, a movable contact for engagement with the spring contact portion of the first contact and arranged to depress said yielding portion to 70 toward the supporting base, a stationary stop shoulder positioned in the path of rebound of the yielding portion of the spring contact, said spring contact having a vibration checking extension on the yielding portion 75 thereof positioned to engage the stop shoulder aforesaid when said yielding portion is freed from engagement with the movable contact member.

CLARENCE D. PLATT.
